CLAIM

We claim the ornamental design for in-wall device mount interface, as shown.

DESCRIPTION

FIG. 1 is a front perspective view of a in-wall device mount interface according to an embodiment of the invention;

FIG. 2 is a front elevation view of a in-wall device mount interface according to an embodiment of the invention;

FIG. 3 is a side elevation view of the in-wall device mount interface depicted in FIG. 1;

FIG. 4 is a bottom plan view of the in-wall device mount interface depicted in FIG. 1;

FIG. 5 is a top plan view of the in-wall device mount interface depicted in FIG. 1;

FIG. 6 is a rear elevation view of the in-wall device mount interface depicted in FIG. 1; and,

FIG. 7 is an elevation view of the in-wall device mount interface of the side opposite that depicted in FIG. 3.

The broken-line disclosure in the views is for illustrative purposes only and forms no part of the claimed design.
